DISPENSER FOR SHEET MATERIAL

Carl A. Flood, Framingham, Mass., assignor to
Dennison Manufacturing Company, Framing-
ham, Mass., a corporation of Massachusetts

Application February 19, 1943, Serial No. 476,424

13 Claims. (Cl. 206—58)

This invention relates to dispensers for sheet material and more particularly to devices for dispensing a strip of tape having labels or other sheet material temporarily adhering to one side of the tape with tacky adhesive which readily peels off the tape. In devices of this kind it is possible to peel the tape off the labels and to project the labels successively from the device by drawing the tape over a sharp edge so that the labels are projected out of the device instead of following the tape around the sharp edge. For this purpose it is desirable to keep the tape from arching away from the edge as it approaches the edge, inasmuch as that would permit the labels to follow the tape around the edge instead of being projected out of the device away from the tape. It is also desirable to cause the tape to leave the edge in the opposite direction from which it approaches the edge, more fully to counteract the tendency for the labels to follow the tape around the edge instead of being projected therefrom.

The objects of the present invention are to provide a dispensing device which is simple and rigid in construction, which can be loaded and threaded quickly and easily, which has means for guiding the tape as it approaches or leaves the aforesaid edge or both, which means is simple and economical to produce, which is effective and reliable in operation, and which also provides a hard smooth peeling edge. Thus the guide means is particularly adapted for use on cardboard boxes or other containers the walls of which are too soft to provide a good permanent peeling edge.

In one aspect the present invention involves a guide for an elongate strip of sheet material which is adapted to be attached to a container, the guide having a lip extending from one end of the guide toward the other end in spaced relation to the back of the guide so that the guide may be attached to the container by sliding an edge of the container under the lip, or by folding the lip over the edge, and a part extending around an edge of the strip and thence along the front of the strip. Preferably the guide is in the form of a flat tube formed by bending a sheet of thin metal to form two juxtaposed relatively wide sides interconnected at the opposite edges by two narrow sides.

In another aspect the invention comprises a package including a strip of tape and sheet material temporarily adhering to the side of the tape with tacky adhesive which readily peels off the tape, together with a container having an outlet through which the tape may be pulled endwise

and a wall having an edge adjacent the outlet and a guide fitted over the edge with portions extending along the inner and outer sides of the wall, the aforesaid portions being integrally interconnected by a peeling edge extending around the aforesaid edge, the peeling edge being sharp enough to peel the tape away from the material and project the latter from the container when the tape is pulled through the aforesaid outlet, and the aforesaid outer portion of the guide having an integral portion extending around one edge of the tape and thence along the outer face of the tape to hold the tape close to said outer portion of the guide as it leaves said peeling edge, thereby to facilitate the peeling operation and to prevent the tacky material from following the tape around the edge.

In still another aspect the aforesaid container is formed in inner and outer parts which telescope together in a direction parallel to the path of the tape as it leaves the container, the two parts having juxtaposed walls to define said path. One end of the outer part of the container is open to receive the inner end of the other part, and the opposite ends of the parts are sealed to form rigid constructions instead of merely having flaps which tuck in as is customary in pasteboard boxes. The preferred way to seal the ends of the two parts of the container is to secure each of these ends to each of the four adjacent side walls of each part of the container.

For the purpose of illustration a typical embodiment of the invention is shown in the accompanying drawing in which

35 Fig. 1 is a side elevation;
Fig. 2 is a plan view;

Fig. 3 is a section on line 3—3 of Fig. 1;

Fig. 4 is a section on line 4—4 of Fig. 1;

40 Fig. 5 is a side view with the two parts of the container separated and with a portion of the outer part broken away;

Fig. 6 is a plan view of the blank from which the guide clip is formed;

Fig. 7 is a perspective view of the clip in inverted position after it has been partially shaped and is ready to be applied to the container; and

Fig. 8 is a side view of the clip in the same condition shown in Fig. 7, with parts shown in central, longitudinal section.

50 In the particular embodiment of the invention chosen for the purpose of illustration the container comprises inner and outer parts 1 and 2 which telescope together in the direction of the arrows in Fig. 5 to the position shown in Fig. 1.

55 The inner part 1 comprises side walls 3, a top 4,

a bottom 5 and a closed end 6, the opposite end being open. The outer part 2 comprises side walls 7, a top 8, a bottom 9 and a closed end 12, the opposite end being open to receive the inner part. The top of each part is integral with the side walls, and the bottom of each part comprises two overlapping flaps which are cemented together face to face, the upper flap being designated 10 in Figs. 3 and 4. The closed end of the outer part comprises an outer flap 12 on the left side wall (Fig. 4), a flap 13 on the right side wall, a flap 14 on the top 8 and a flap 16 on the bottom 9. The flap 12 substantially covers the end of the box and the flaps 13, 14 and 16, which are cemented to the flap 12 in overlapping relationship, substantially cover the inner face of the flap 12 without overlapping each other, the sides of the flaps 13, 14 and 16 being beveled so that their edges substantially meet without overlapping. The end 6 of the inner part of the container is closed in similar manner.

As shown in Fig. 5 the sides 3 of the inner part of the container are cut away to the line 17, the overlying portion 18 of the top 4 being folded in and cemented to the inner face of the top to form a rounded edge 19 over which the strip of labels may slide easily in leaving the box.

As shown in Fig. 5 the label strip comprises ribbon or tape T formed of paper or cloth and a series of labels L secured to one side of the tape with normally tacky adhesive which readily peels off the tape. The strip is preferably wound in a roll as indicated at R, the labels being on the side of the tape facing toward the center of the roll.

Mounted on the top of the outer part of the container near the open end of this part is a clip C which is formed from the metal blank shown in Fig. 6. This blank comprises a top 21 and a bottom 22 interconnected by an integral side wall 23. The opposite ends of the blank comprise flanges 24 and 25 which, when bent into overlapping relationship as shown in Figs. 7 and 8, constitute the other side wall of the clip. The flange 24 has a projecting tongue 26 adapted to be bent over into overlapping relationship with the bottom 22. At one end the bottom has integral tongues 27 for anchoring the clip to the box and at the other end it has a lip 28 adapted to be bent over the edge of the top 8 to form a smooth edge 29 (Fig. 5). The top 21 also has a lip 31 bent inwardly to the position shown in Fig. 8 to form a rounded edge 32. As shown in Fig. 8 one end of the top 21 may be bent up to form a flaring mouth 33. The lip 28 may be bent in either before or after the clip is attached to the box, but it is preferably bent over the edge of the box at the time the clip is attached to the box, the tongues 27 being bent up along the inside of the top at the same time the lip 28 is folded over the edge.

With the strip of labels in the position shown in Fig. 5 the two parts of the container are telescoped together with the strip projecting out through the confined space between the tops 4 and 8 of the inner and outer parts. Then, with the labels stripped off of the projecting part of the tape, the tape is threaded through the flat tubular passageway in the clip with the end of the tape projecting from the mouth 33. By pulling on the projecting end of the tape it is peeled over the edge 29 and, owing to the stiffness of the labels and the sharpness of the peeling edge, the labels are projected from the container in line with the path along which the strip approaches

the peeling edge. When the foremost label is almost free from the tape it swings upwardly into engagement with the edge 32. When it first engages the edge the label stands in substantially a vertical position, with its lower end still resting on the tape. If the tape is pulled farther the lower end of the label enters the passageway in the clip, dragging the tacky side of the label against the rounded edge 32 and swinging the label back in a counterclockwise direction. By the time the label has reached approximately the position shown in Fig. 1 the aforesaid drag causes the tape to pull loose from the label. At this time the next label has started to emerge as shown in Fig. 1. In either of the aforesaid positions the label may be grasped between thumb and finger and removed, or it may be swung down into contact with the top of the clip in the position shown in Fig. 2 for the purpose of writing on its outer unglued surface. In this position one end projects enough to grasp it for the purpose of removing the label.

If the edge 32 were sharp instead of rounded the label would not stick tight enough to act as described; it would either topple over upon the top of the clip or it would follow the tape through the clip. If the label topples over on the clip it must be pulled loose; and if the label is pulled into the clip it tends to damage the label and clog the passageway in the clip.

It should be understood that the present disclosure is for the purpose of illustration only and that this invention includes all modifications and equivalents which fall within the scope of the appended claims.

I claim:

1. A package comprising a strip of tape and sheet material temporarily adhering to one side of the tape, a container having an outlet through which the strip may be pulled, the container having an edge adjacent said outlet over which the tape may be peeled to project the labels therefrom, the container also having a guide spaced from said edge on the side opposite to the outlet to guide the tape as it leaves said edge, the guide having a smooth edge approximately parallel to said edge and adjacent to for catching the label as it is projected from the tape.

2. A package comprising a strip of tape and sheet material temporarily adhering to one side of the tape, a container having an outlet through which the strip may be pulled, the container having an edge adjacent said outlet over which the tape may be peeled to project the labels therefrom, the container also having a guide spaced from said edge on the side opposite to the outlet to guide the tape as it leaves said edge, the guide comprising sheet metal bent to form a rounded edge approximately parallel to said edge and adjacent to for catching the label as it is projected from the tape.

3. A package comprising a strip of tape and sheet material temporarily adhering to one side of the tape with tacky adhesive which readily peels off the tape, a container having an outlet through which the strip may be pulled along a predetermined path, the container being formed in inner and outer parts, one end of the outer part being open and one end of the inner part telescoping into said open end in a direction parallel to said path, the ends of the parts opposite said ends being sealed to form rigid constructions, the two parts having juxtaposed side walls to define said path, said side wall of the inner part terminating short of the sealed end

of the outer part to facilitate entry of the strip into said path, and a clip fitted over the edge of said side wall of the outer part at the open end of the outer part over which the tape may be peeled away from said sheet material as the strip is pulled from the container.

4. A package comprising a strip of tape and sheet material temporarily adhering to one side of the tape with tacky adhesive which readily peels off the tape, a container having an outlet through which the strip may be pulled along a predetermined path, the container being formed in inner and outer parts which telescope together in a direction parallel to said path, the two parts having juxtaposed walls to define said path and a clip fitted on the end of said wall of the outer part over which the tape may be peeled away from said sheet material as the strip is pulled from the container, said clip comprising a guide spaced from the outer side of the outer part to form a guideway for the strip after it is peeled from the sheet material.

5. A package comprising a strip of tape and sheet material temporarily adhering to one side of the tape with tacky adhesive which readily peels off the tape, a container having an outlet through which the strip may be pulled along a predetermined path, the container being formed in inner and outer parts, one end of the outer part being open and one end of the inner part telescoping into said open end in a direction parallel to said path, the ends of the parts opposite to said ends being sealed to form rigid constructions, the two parts having juxtaposed side walls to define said path, and a clip fitted on the end of said side wall of the outer part over which the tape may be peeled away from said sheet material as the strip is pulled from the container, said clip comprising a guide spaced from the outer side of the outer part to form a guideway for the strip after it is peeled from the sheet material.

6. A package comprising a strip of tape and sheet material temporarily adhering to one side of the tape with tacky adhesive which readily peels off the tape, a container having an outlet through which the strip may be pulled along a predetermined path, the container being formed in inner and outer parts which telescope together in a direction parallel to said path, the telescoping ends of the parts being open and the opposite ends being sealed to make the parts rigid, the two parts having juxtaposed walls to define said path, and a clip fitted on the end of said wall of the outer part over which the tape may be peeled away from said sheet material as the strip is pulled from the container, the strip extending through the open end of the inner part and thence between said juxtaposed walls to said clip, said clip comprising a guide spaced from the outer side of the outer part to form a guideway for the strip after it is peeled from the sheet material.

7. A package comprising a strip of tape and sheet material temporarily adhering to one side of the tape with tacky adhesive which readily peels off the tape, a container formed in two parts having open ends which telescope together with their side walls in close juxtaposition, the walls at the opposite ends of the parts being secured to each of the four side walls of the parts respectively to make the parts rigid, and a clip fitted on the end of said side walls of the outer part over which the tape may be peeled away from

said sheet material as the strip is pulled from the container, the strip extending through the open end of the inner part and thence between two of said side walls to said clip, said clip comprising a guide spaced from the outer side of the outer part to form a guideway for the strip after it is peeled from the sheet material.

8. A package comprising a strip of tape and sheet material temporarily adhering to one side of the tape with tacky adhesive which readily peels off the tape, a container formed in two parts having open ends which telescope together with their side walls in close juxtaposition, the walls at the opposite ends of the parts being secured to each of the four side walls of the parts respectively to make the parts rigid, and a clip fitted on the end of said side walls of the outer part over which the tape may be peeled away from said sheet material as the strip is pulled from the container, the strip extending through the open end of the inner part and thence between two of said side walls to said clip, the open end of the inner part being beveled on the side adjacent said walls, said clip comprising a guide spaced from the outer side of the outer part to form a guideway for the strip after it is peeled from the sheet material.

9. A package comprising a strip of tape and sheet material temporarily adhering to one side of the tape with tacky adhesive which readily peels off the tape, a container having an outlet through which the strip may be pulled along a predetermined path, the container being formed in inner and outer parts, one end of the outer part being open and one end of the inner part telescoping into said open end in a direction parallel to said path, the ends of the parts opposite to said ends being sealed to form rigid constructions, the two parts having juxtaposed side walls to define said path, and a flat tubular guide for said strip, the guide comprising a piece of sheet metal bent to form parallel top and bottom parts and sides, one side being integral with both top and bottom and the other side being integral with only one of the parts, said bottom being extended at one end to form a lip which is folded back in spaced relation thereto so that the tubular guide may be attached to said container by sliding an edge of the container under the lip and being extended at the other end to form a tongue for anchoring the guide to the container.

10. A package comprising a strip of tape and sheet material temporarily adhering to one side of the tape with tacky adhesive which readily peels off the tape, a container having an outlet through which the strip may be pulled along a predetermined path, the container being formed in inner and outer parts which telescope together in a direction parallel to said path, the two parts having juxtaposed walls to define said path, and a flat tubular guide for said strip, the guide comprising a piece of sheet metal bent to form parallel top and bottom parts and sides, one side being integral with both top and bottom and the other side being integral with only one of the parts, said bottom part being extended at one end to form a lip which is folded back in spaced relation thereto so that the tubular guide may be attached to said container by sliding an edge of the container under the lip.

11. A flat tubular guide for a strip of peelable labels comprising a piece of sheet metal bent to form parallel top and bottom parts and sides, one side being integral with both top and bottom and

the other side being integral with only one of the parts, said bottom part being extended at one end to form a lip which is folded back in spaced relation thereto so that the tubular guide may be attached to a container by sliding an edge of the container under the lip.

12. A flat tubular guide for a strip of peelable labels comprising a piece of sheet metal bent to form parallel top and bottom parts and sides, one side being integral with both top and bottom and the other side being integral with only one of the parts, said bottom part being extended at one end to form a lip which is folded back in spaced relation thereto so that the tubular guide may be attached to a container by sliding an edge of the container under the lip and being extended

at the other end to form a tongue for anchoring the guide to the container.

13. A flat tubular guide for a strip of peelable labels comprising a piece of sheet metal bent to form parallel top and bottom parts and sides, one side being integral with both top and bottom and the other side being integral with only one of the parts, the latter side having a flange overlapping the other part, said bottom part being extended at one end to form a lip which is folded back in spaced relation thereto so that the tubular guide may be attached to a container by sliding an edge of the container under the lip and being extended at the other end to form a tongue for anchoring the guide to the container.

CARL A. FLOOD.
